DESIGN FOR A DRINK MIXER

Herman W. Zimmerman, North Newington, Conn.

Application January 24, 1946, Serial No. 125,931

Term of patent 7 years

(Cl. D44—1)

To all whom it may concern:

Be it known that I, Herman W. Zimmerman, a citizen of the United States, residing at North Newington, in the county of Hartford and State of Connecticut, have invented a new, original, and ornamental Design for a Drink Mixer, of which the following is a specification, reference being had to the accompanying drawing, forming a part thereof.

In the drawing:

Fig. 2 is a plan view of the mixer shown in Fig. 1.

I claim:

The ornamental design for a drink mixer, as shown.

HERMAN W. ZIMMERMAN.
